(57) **CLAIM**

We claim the ornamental design for a removable data cartridge, as shown and described.

DESCRIPTION

FIG. 1 is a top plan view of a removable data cartridge showing our new design;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a back elevation view thereof; and,

FIG. 7 is a perspective view thereof.

The portions shown in broken line are for illustrative purposes only and form no part of the claimed design.
